[57] CLAIM

The ornamental design for telephone dialer adjunct, as shown and described.

DESCRIPTION

FIG. 1 is a front, top and right side perspective view of a telephone dialer adjunct showing our new design;

FIG. 2 is a similar perspective view thereof with the rear lid portion of the top being opened to identify a recessed area for operative associated relationship.

FIG. 3 is a top plan view thereof;

FIG. 4 is a right side elevational view;

FIG. 5 is a left side elevational view thereof;

FIG. 6 is a bottom plan view;

FIG. 7 is a front view of the telephone dialer adjunct; and

FIG. 8 is a rear view thereof.

The broken line showing of symbols in circular key buttons in FIGS. 1, 2, and 3, and of recessed keyboard characterization in FIG. 2 is for illustrative purposes only and forms no part of the claimed design.
